UNITED STATES PATENT OFFICE.

D. DEAN READ, OF BOSTON, MASSACHUSETTS.

ELEVATED RAILWAY.

SPECIFICATION forming part of Letters Patent No. 379,181, dated March 6, 1888.

Application filed December 24, 1887. Serial No. 258,891. (No model.)

To all whom it may concern:

Be it known that I, D. DEAN READ, of Boston, county of Suffolk, State of Massachusetts, have invented an Improvement in Elevated 5 Railways, of which the following description, in connection with the accompanying drawings, is a specification, like letters on the drawings representing like parts.

My invention relates to an elevated-railway 10 structure composed of trusses supported on suitable columns or uprights above and below the cars, which have trucks above and below co-operating with rails on the upper and under trusses, substantially as shown in Letters Patent 15 No. 373,605, granted to me November 22, 1887, to which reference may be had.

The present invention consists, mainly, in 20 details of construction of the trusses and rails by which angle-iron and rails of usual shape may be employed throughout the structure without requiring the rolling of the special shapes, as in the structure shown in the patent referred to.

The present invention consists, mainly, in 25 providing the top flange of the lower truss and the bottom flange of the upper truss with lateral arms, on which are supported railway rails of the usual T shape, which rest on longitudinal supports between the said lateral 30 arms, and, when required, may be stiffened by secondary trussing.

The invention also consists in various other details, which will be hereinafter pointed out.

Figure 1 is a side elevation of a portion of 35 a railway structure embodying this invention; Fig. 2, a transverse sectional view thereof; Fig. 3, a modification to be referred to; Fig. 4, an enlarged sectional detail of the lower truss; Fig. 5, a detail showing a portion of said lower 40 truss in side elevation; Fig. 6, an end elevation of one of the lower trucks of the car and the co-operating portion of the truss; Fig. 7, a sectional detail of the lower portion of the upper truss; Fig. 8, a similar view showing also a 45 portion of the upper truck; Fig. 9, a side elevation of a portion of the upper truck, and Fig. 10 a plan view of a portion thereof.

The general arrangement of the structure, consisting of uprights or columns *a*, extended

above the level at which the cars run and constituting supports for cables *b b'*, which co-operate with the said columns to support the lower or main truss, *d*, and upper truss, *f*, is substantially the same as in my patent hereinbefore referred to. 50

In the present invention the upper chord, *d'*, (see Figs. 4, 5, and 6,) of the lower truss has secured to it from point to point along its length transverse arms or cross-pieces *g*, which in turn support at their ends longitudinal beams *h*, on which rest the rails *i*, which are of the usual T shape. 55

The cross-pieces *g* are provided at their ends with ears *g'*, that engage the flanges of the rails *i*, which are securely fastened upon the beams *h* by clamp-pieces *k*, bolted to the said arms *g* between the rails *i* and the central truss, *d*. 60

The outer ends of the cross-pieces *g* are supported by braces *m*, extending to the lower chord, *d'*, of the truss, as shown in Fig. 4. 7c Longitudinal pieces of angle-iron, *n*, are fastened to the upper ends of said braces, the lower edges of which pieces of angle-iron co-operate with guard-wheels *n'*, connected with braces *n''*, extending downward from the car-body and serving to prevent the cars from overturning in case an accident should occur to the running-gear at the top of the car. The strips *n* also contribute to the support of the beams *h* and rails *i* thereon. 75 80

The rails *i* are of comparatively narrow gage, and are not depended upon solely to afford sufficient stability for the running of the cars, which are retained in their upright position or prevented from overturning by the 85 upper truss, *f*, (see Figs. 7 and 8,) the lower chord, *f'*, of which is provided with cross-pieces *g''*, having at their outer ends upturned projections *g'''*, to which are fastened longitudinal beams *h'*, on which are supported the rails *i'*, which co-operate with the trucks or hangers at the top of the car-body, as shown in Fig. 2. 90

The arms *g''* are strengthened by braces *m'*, extending to the upper chord of the upper 95 truss, and the rails *i'* are fastened by clamps *k'*, bolted to the said cross-pieces *g''*.

The upper trucks or hangers may consist of

double-flanged wheels o , (see Figs. 8 and 9,) journalled on yokes o' , as shown in Figs. 9 and 10, swiveled upon rods o^2 , having an enlargement at the lower end, as shown in Fig. 9, by 5 which they are fastened in suitable sockets connected with the frame-work at the top of the car.

The lower trucks consist of a frame, p , (see Fig. 6,) swiveled upon the car-body and provided with bearings p' for the journals of the axles of the wheels p^2 , which may have a single inner flange, as in the usual railway construction.

The wheel-base afforded by the lower track, 15 i , is sufficient to support the cars, and may be depended upon alone, as shown in Fig. 3, at switches or places where it is desirable to discontinue or form a break in the upper truss, which affords additional stability in the main 20 part of the track, so that the cars may run safely at high speeds.

When required, the rails i and i' may be stiffened by secondary trussing, as represented at t , Figs. 1, 4, 5, and 7, consisting of tie-rods 25 fastened to the lower flange of the beams h and h' .

The upper chord, d' , of the lower truss may also support a longitudinal box or trough, u , composed of angle-iron, for the purpose of inclosing and protecting a propelling-cable, w , supported on friction-wheels w' , having bearings in the sides of said trough, and the lower chord of the upper truss may be provided with a box, v , also composed of angle-iron, as shown, in which is inclosed an electric conductor, v' , which may be employed when the cars are propelled by electricity.

I claim—

1. An elevated-railway structure comprising a supporting-truss centrally located below the cars and having its upper member provided with cross-pieces supporting longitudinal beams and T-rails thereon, combined with an upper truss provided with rails, the said 40 upper and lower trusses co-operating with cars having trucks above and below co-operating with said rails on the upper and lower trusses, substantially as described.

2. An elevated-railway structure comprising a truss beneath the cars having on its upper member cross-bars and rails supported at the ends of said cross-bars, combined with a longitudinal trough supported on said truss between said rails, substantially as and for the 55 purpose described.

3. In a railway structure, a truss centrally located with relation to the cars, having one of its chords provided with cross pieces and railssupported at the ends of said cross-pieces, 60 co-operating with trucks connected with the car-body, and a longitudinal trough or box supported on the said chord of the truss, substantially as and for the purpose described.

4. In an elevated-railway structure, a truss 65 centrally located with relation to the cars, hav-

ing its upper member provided with cross-pieces, combined with rails supported on said cross-pieces, and longitudinal strips of angle-iron having their horizontal portion or flange connected with the under sides of said cross-pieces and their vertical portion or flange projecting downward from said cross-pieces, substantially as and for the purpose described. 70

5. In an elevated-railway structure, a truss centrally located below the cars, having its 75 upper member provided with cross-pieces, and rails supported on the ends of said cross-pieces, combined with braces extending downward and inward from the ends of said cross-pieces to lower chord of the truss, substantially as described. 8c

6. A truss and cross-pieces supported on the chord thereof, provided with upturned ends and rails supported on said cross-pieces and engaged by the upturned ends thereof, and 85 clamps secured to the said cross-pieces between the rails and engaging the lower flanges of said rails, substantially as described.

7. The main truss, combined with cross-pieces supported on one of the chords thereof, 90 rails supported on the ends of said cross-pieces, and secondary trussing for stiffening said rails, substantially as described.

8. In a railway structure, a truss centrally located above the cars, having its lower chord 95 provided with cross-pieces, and beams and rails supported at the ends of said cross-pieces, substantially as described.

9. In an elevated-railway structure, a single truss centrally located beneath one line of 100 track, having its upper member provided with cross-pieces and rails supported at the ends of said cross-pieces, and longitudinal strips projecting down from the end of said cross-pieces, combined with cars having trucks beneath them provided with wheels that run on said rails, and braces n^2 , extending downward from the car-body and provided with guard-wheels running on said downwardly-projecting strips, substantially as and for the purpose described. 105

10. A truss provided with rails forming a track above the cars, combined with cars having hangers, each composed of a pair of double-flanged wheels journalled at the opposite ends 115 of yokes o' , and rods having a swivel-connection with the said yokes between said wheels and with the upper part of the car-body, substantially as described.

11. The combination of a series of supporting posts or uprights, with a truss supported on the said uprights and centrally located with relation to the line of track, the upper chord of said truss being provided with cross-pieces and rails supported at the ends of said cross-pieces, constituting a single line of railway-track, and braces extending from the outer ends of said cross-pieces downwardly and inwardly to the lower chord of the truss, substantially as described. 125 130

12. A truss having one chord provided with cross-pieces, combined with braces extending from the ends of said cross-pieces to the other chord of said truss and rails supported on the 5 ends of said cross-pieces, and tie-rods forming the secondary trusses beneath the said rails, substantially as described.

In testimony whereof I have signed my name to this specification in the presence of two subscribing witnesses.

D. DEAN READ.
